UNITED STATES PATENT OFFICE.

JOHN FRANKLIN WILKINSON, OF GLOUCESTER, MASSACHUSETTS.

FOOT-POWER DRIVING MECHANISM.

No. 927,201.

Specification of Letters Patent.

Patented July 6, 1909.

Application filed August 8, 1906. Serial No. 329,706.

To all whom it may concern:

Be it known that I, JOHN FRANKLIN WILKINSON, of Gloucester, in the county of Essex and State of Massachusetts, have invented certain new and useful Improvements in Foot-Power Driving Mechanism, of which the following is a specification.

This invention relates to a foot-power mechanism or motor employing a treadle for 10 rotating a crank-shaft, and a clutch for preventing backward rotation of the crank-shaft and driving-wheel when the treadle is operated.

In Letters Patent No. 592,577, granted to me October 26, 1897, I have set forth a foot-power driving mechanism comprising a treadle connected by a pitman with the crank-shaft, and a supplemental treadle connected with a clutch on the crank-shaft, the 20 construction being such that the crank-shaft is rotated freely in one direction by a movement of the treadle, the clutch locking it against rotation in the opposite direction. The depression of the supplemental treadle causes the clutch to impart a partial rotation to the crank-shaft, sufficient to move the shaft from a dead-center position. In the construction of the said former patent, the operator's foot is required to coöperate 25 with two treadles or treadle portions, namely, the usual main treadle connected by a pitman with the crank-shaft, and a supplemental treadle connected with the clutch, the supplemental treadle being normally 30 yieldingly supported by the main treadle and capable of being depressed by the operator's foot to the level of the adjacent portion of the main treadle. The said two-part treadle construction is somewhat complicated, and leaves something to be desired in 35 the way of simplicity, ease, and efficiency of operation.

The present invention has for its object to provide a simplified and improved construction of that portion of a foot-power mechanism of the character described, which includes the treadle or part on which the operator's foot bears.

The invention consists in the improvements which I will now proceed to describe and claim.

Of the accompanying drawings, forming a part of this specification,—Figure 1 repre-

sents a front elevation of a foot-power mechanism embodying my invention, applied to 55 the supporting frame of a sewing-machine. Fig. 2 represents a section on line 2—2 of Fig. 1, and an elevation of the mechanism at the right of said line. Fig. 3 represents a perspective view of the rocking base which 60 supports the treadle. Fig. 4 represents an enlargement of a portion of Fig. 2.

The same reference characters indicate the same parts in all the figures.

In the drawings,—12 represents a crank- 65 shaft journaled in suitable bearings.

13 represents a driving-wheel fixed to the crank-shaft, the hub of the driving-wheel having a circular cavity, the inner wall 14 of which constitutes a clutch member adapt- 70 ed to coöperate with a clutch-dog or member 15 mounted to oscillate on a plate 16 which is fitted in the cavity of the hub of the driving-wheel and is adapted to rotate independently of the crank-shaft and driving- 75 wheel. The clutch member 15 is adapted to slip loosely on the friction surface of the driving-wheel when the latter is rotating in a forward direction, and to engage said friction surface and prevent backward rotation 80 of the crank-shaft and driving-wheel, the operation in this respect being the same as that described in my former patent. For convenience, I will hereinafter refer to the member 15 and the part which carries it as 85 the clutch.

To the lower portion of the supporting frame is fulcrumed a part which I term a rocking base. This part, in the construction here shown, comprises a body portion which 90 includes two side arms 17 and 18, and a connecting cross-bar 19. The body portion is fulcrumed to the supporting frame by means of pivots 20 affixed to the frame and engaging sockets 20' in the arms 17 and 18 95 and located at points near their inner ends. The body portion of the rocking base is pro- 100 vided with an extension 30, projecting from one side of the axial line of the pivots and forming the longer arm of a lever, the shorter arm of which is formed by the body portion of the rocking base. The extension 30 is preferably formed on the arm 18 of the body portion.

21 represents a treadle, which is connected 105 by a rod 22 to the arms 17 18 of the rocking

base, the rod entering sockets 22' in said arms and constituting a pivotal connection between the said treadle and arms, said connection being preferably near the outer ends 5 of the arms and one edge of the treadle. The treadle projects from its pivotal connection with the arms across the body portion of the rocking base and beside the lever extension 30.

10 23 23 represent springs which are interposed between the treadle 21 and the cross-bar 19 of the rocking base. The said springs are adapted to be compressed by a downward movement of the treadle and to impart 15 such movement yieldingly to the rocking base. The extension 30 of the rocking base is connected by a pitman 25 with the crank shaft 12, and the treadle 21 is connected by a rod 26 with an ear 27 affixed to the clutch 20 plate 16. The oscillation of the treadle therefore oscillates the clutch, and imparts motion yieldingly through the springs 23 to the rocking base, which, in turn, imparts 25 a rotary motion to the crank shaft through the pitman 25.

It will be seen that the treadle which is adapted to move independently of the rocking base, when depressed causes a compression of the springs 23, so that not only is 30 motion transmitted from the treadle to the rocking base through said springs, but power is also stored in the springs by the downward movement of the operator's foot on the treadle, this power being imparted to the 35 crank shaft, through the arm 30 and rod 25 to compensate for temporary increase of resistance to the running of the machine, whether by the addition of more work or from other causes. The upward movement 40 of the treadle is assisted by the springs, but does not depend wholly upon them, but in part upon the pressure exerted by the operator's heel upon the forward portion of the treadle at the outer side of the springs. It 45 will also be seen that the freedom of independent movement of the treadle and the yielding connection between it and the rocking base, enables the amplitude of the vibrations of the treadle to be reduced to the 50 minimum. While the rocking base must necessarily oscillate in a path of fixed extent or amplitude, the treadle, which is directly connected only with the clutch, can move in a path of varying and lesser amplitude, 55 hence the toe portion of the operator's foot is not required to rise and fall to the extent that would be required if direct contact between the foot and the rocking base were required. I have found in practice that by 60 giving the treadle a direct connection only with the clutch, and providing the rocking base yieldingly connected with the treadle as the means for imparting motion from the treadle to the crank shaft, the operation of 65 the machine is materially simplified, the

operator having but one treadle part to manage, instead of having two treadle parts as heretofore. I have also found that the operation is attended with less jar or jerking motion and vibration than in my former 70 constructions.

I prefer to make the springs 23 of helical form, and so proportion them that their convolutions will close and act as a stop to limit the independent downward movement of the 75 treadle, so that the treadle cannot strike the rocking base, the noise and jar which would attend direct contact between the treadle and the base, being avoided. The arms 17 18 of the body portion of the rocking base are 80 preferably provided with stop ears 28, which project under the forward portion of the treadle.

It will be seen that the treadle presents a heel bearing directly over the pivotal connection of the treadle to the base, and at one side of the fulcrum of the base, and a toe bearing at the opposite side of said fulcrum. A downward movement of the operator's heel is therefore imparted directly to the 90 rocking base through the pivot connecting the treadle to the base, while a downward movement of the toe causes the treadle to swing downwardly on its pivot and impart a corresponding movement to the rocking 95 base.

I claim:

1. The combination with a crank shaft and a clutch thereon, of a support, a rocking base fulcrumed on the support, and formed as a lever, a connection between said lever and the crank shaft, a treadle pivoted to the said base and adapted to oscillate independently thereof, a connection between said treadle and the clutch, and a power-storing and delivering connection between the treadle and the base.

2. The combination with a crank shaft and a clutch thereon, of a support, a rocking base fulcrumed on the support, and formed as a lever, a treadle pivoted to the base and adapted to oscillate independently thereof, connections between said base and treadle to the crank shaft and clutch respectively, and a spring engaged with the treadle 115 and base and adapted to yieldingly transmit motion from one of said parts to the other.

3. In a driving mechanism of the character stated, a support, a rocking base constituting a two-armed lever, and comprising a 120 body portion fulcrumed on said support, and forming the shorter lever arm, and an extension forming the longer lever arm, a treadle pivoted to the shorter arm of the body portion, and extending across the fulcrum of 125 the lever, and springs interposed between the treadle and the body portion, and adapted to yieldingly transmit motion from the treadle to the rocking base.

4. In a foot power driving mechanism, a 130

support, a rocking base fulcrumed to said support, and formed as a two-armed lever, a treadle pivoted to the shorter arm of the rocking base at one side of its fulcrum, and extending across the fulcrum, the said treadle presenting a heel-bearing directly over the pivotal connection of the treadle to the base, and at one side of the fulcrum,

and a toe-bearing at the opposite side of said fulcrum.

In testimony whereof I have affixed my signature, in presence of two witnesses.

JOHN FRANKLIN WILKINSON.
